UNITED STATES PATENT OFFICE.

LAFE SWANK AND JAMES E. VAN DEVENTER, OF ANDERSON, INDIANA, ASSIGNEES
TO DWIGGINS WIRE FENCE COMPANY, OF ANDERSON, INDIANA, A CORPORATION
OF INDIANA.

WIRE-FENCE LOOM.

1,380,165.

Specification of Letters Patent. Patented May 31, 1921.

Application filed January 23, 1919. Serial No. 272,641.

To all whom it may concern:

Be it known that we, LAFE SWANK and JAMES E. VAN DEVENTER, citizens of the United States, residing at Anderson, in the 5 county of Madison and State of Indiana, have invented a new and useful Wire-Fence Loom, of which the following is a specification.

In the operation of machines for producing wire fence of that type comprising several continuous parallel running wires, and lateral—or vertical—wires attached to the running wires, it is generally customary to move the running wires through the machine by a step-by-step forwarding feed and to attach the cross wires during the periods of rest of the longitudinal wires.

Such an operation generally results in an unevenness of tension in the running wires 10 and in the necessity of repeatedly stopping and starting the storage-roll of finished product.

The object of our present invention is to provide means, in a machine of the general 25 type indicated, for insuring uniformity of tension in the various longitudinal wires and for handling the product within the machine, in such manner that the storage-roll may be continued in its rotation, even 30 during the periods of non-movement of the longitudinal wires at that point in the machine where the lateral wires are being applied.

The accompanying drawings illustrate our 35 invention. Figure 1 is a side elevation of a machine embodying our invention; Fig. 2 a fragmentary vertical section of a modification; Fig. 3 a fragmentary vertical section on line 3—3 of Fig. 4 of the drum-driving 40 train of the form shown in Fig. 1; Fig. 4 a plan of the parts shown in Fig. 3; and Fig. 5 a fragmentary plan of portions shown in Fig. 1.

In the drawings, 10 indicates one of the 45 running, or longitudinal, wires which become part of the finished fabric. Each of these wires comes from a storage roll 11, the several storage rolls being mounted for independent rotation in any suitable support 50 12. The several wires 10 pass to and through a tensioning device 13 of well known type, comprising rolls 14, 15, 16, the wires passing under roll 14, over roll 15 and under roll 16, and roll 15 being vertically adjustable in order to vary the resist-

ance of the roll combination to the passage of the wires.

Wires 10 pass from the tensioning device 13 to and beyond a point in the machine where lateral wires may be applied thereto 60 (approximately at the point X indicated in Fig. 1) and from thence to feeding mechanism by which the wires are advanced, relative to the point X, in a step-by-step advancement, being supported at suitable 65 points, as at S and 30 and 31.

We have found that, if the wires 10 pass directly from the storage rolls 11 to the tensioning device 13, the various wires will be variably tensioned, the variations being determined by the different and constantly varying resistances offered by the several storage rolls, added to the constant resistance of the device 13. In order that this variation might be minimized, it has been 70 customary to adjust device 13 so as to place the wires 10 under a very heavy tension, thereby reducing the proportionate resistances of the storage rolls 11, but such an adjustment of device 13 is inadvisable. In 80 order to overcome the difficulty mentioned above (which results in an uneven product having non-parallel transverse wires) we pass all of the wires 10 loosely over, or through, what we have called a kicker bar 85 20 which is arranged to engage wires 10 between device 13 and rolls 11. Bar 20 is carried by arms 21 of a rock shaft 22 and this rock shaft is rocked, during periods of non-movement of wires 10 at point X, by any 90 suitable means to a sufficient extent to draw from rolls 11 enough wire to supply, without resistance from rolls 11, enough wire for the next advancement of wires 10 at point X. By this arrangement, the device 13 may be so 95 adjusted as to offer only enough resistance to the passage of wires 10 to keep them properly taut at point X.

In the drawings, shaft 22 is shown as being rocked by link 23, lever 24, link 25, 100 cross head 26, strap 27 and eccentric 28 carried by shaft 29, said shaft controlling a portion of the machine which serves to attach the lateral wires to the running wires and which is not illustrated because it is of 105 well known construction and forms no part of our present invention.

In order that the storage-roll 17 may be driven continuously, and the advancement of wires 10 be step-by-step relative to p

X, the wires 10, to which the lateral wires have been attached, pass from point X to and over an idler 30, thence under an idler 31, over crimping roll 32, and under idler 33 5 to roll 17.

Crimping roll 32 is driven continuously at such a rate of speed that, in any cycle of the lateral-wire attaching means, the wires 10 will be advanced a distance equal 10 to the required spacing of the lateral wires. As these spacings are fairly standard, we have indicated, in Figs. 3 and 4, a train of speed-changing gearing 40, of well known type, by which the desired speeds of roll 32 15 may be attained. In order to provide the desired period of rest of wires 10 at point X, we arrange, between idlers 30 and 31 (Fig. 1) a reciprocating feed bar or roll 41, under which the fabric, comprising wires 20 10 and the attached lateral wires, passes. Roll 41 is carried by arms 42 pivoted conveniently on the axis of idler 31 and each of these arms is oscillated (of course in unison) by a link 43, strap 44, and eccentric 25 45. Link 43 is preferably connected to its arm 42 by a collar 46 adjustable lengthwise on the arm 42 so that the stroke of roller 41 may be varied to properly coöperate with the crimping roll 32. The parts are so 30 adjusted that, when lack of movement of wires 10 relative to point X is desired, roll 41 is moving upward, toward the plane defined by rolls 30 and 31, at a rate at least equal to the forwarding effect produced on 35 wires 10 by the steady advance of roll 32. As soon as a lateral wire has been applied to wires 10, roll 41 moves downward, away from the plane of rolls 30 and 31, so as to augment the forward feeding effect of roll 40 32 on wires 10 by an amount sufficient to produce, in conjunction with roll 32, a forwarding of wires 10 at point X equal to the desired spacing between lateral wires, whereupon the operation is repeated. 45

In the form shown in Fig. 2, the wires 10 pass from point X to idler 30', and thence to crimping roll 32'. Between rolls 30' and 32', the feed roll or bar 41' acts, said bar 41' being carried by arms 42' connected by adjustable collar 46' and link 43', with cross head 26'.

Storage roll 17 will be driven, as is quite common in machines of this type, through a friction clutch 50 in order to make due al-

lowance for the gradually increasing diameter due to accumulation of fabric on the storage roll. 55

By the provision of the roll 41 (or its equivalent) we are able to drive the storage and crimping rolls continuously by the expenditure of much less power than is required by intermittent movement of these parts and we also find it possible to very greatly increase the average speed of advancement of wires 10 through the machine. 60 As a consequence, we are able, by the very simple mechanism described, to very greatly increase the hourly output of machines of this type. 65

We claim as our invention: 70

1. In a fence-fabric machine, the combination of supports between which longitudinal wires are to advance step-by-step, of tension means back of said supports, independent storage rolls back of the tensioning means and delivering independent wires thereto, means acting upon said wires between the tensioning means and storage rolls for intermittently supplying slack in said wires during a period of non-movement of 75 said wires immediately beyond the tensioning means, means acting upon said wires beyond said supports for continuously advancing said wires, and a reciprocatory member acting transversely on the wires behind said continuous advancer for varying the effect of said continuous advancer on the wires between said supports. 80

2. In a fence-fabric machine, the combination of supports between which longitudinal wires are to advance step-by-step, of tension means back of said supports, independent storage rolls back of the tensioning means and delivering independent wires thereto, means acting upon said wires beyond said supports for continuously advancing said wires, and a reciprocatory member acting transversely on the wires behind said continuous advancer for varying the effect of said continuous advancer on the wires between said supports. 90

In witness whereof we have hereunto set our hands at Anderson, Indiana, this 18th day of January, A. D. one thousand nine hundred and nineteen.

LAFE SWANK.
JAMES E. VAN DEVENTER.
